UNITED STATES PATENT OFFICE

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,237,439.

Specification of Letters Patent. Patented Aug. 21, 1917.

Application filed August 7, 1914. Serial No. 855,551.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My present invention relates to carriage feeding or escapement mechanism for type-writing machines and its principal object is to provide new and improved mechanism of the character specified.

To the above and other ends my invention consists in the features of construction, combinations of devices and arrangements of parts hereinafter described and particularly pointed out in the claims.

In the accompanying drawings which illustrate the preferred form of my invention,

Figure 1 is a fragmentary vertical sectional view taken fore and aft of a typewriting machine embodying my invention.

Fig. 2 is a sectional view taken on a plane passing through the axis of the carriage spring drum.

Fig. 3 is a face view taken from the front, of the escapement wheel and associate parts including a section of the carriage rack.

Fig. 4 is a face view of a supporting frame and of the carriage motor and escapement wheel devices mounted thereon, the escapement wheel and associate parts being shown in section.

Fig. 5 is a rear elevation showing the dog rocker shaft and connected parts.

Figs. 6, 7, 8, 9, 10 and 11 are enlarged views showing the escapement dogs and their supporting and controlling devices in various relationships.

As appears from Fig. 1 the main frame of the machine comprises end plates 1 and a connecting top plate 2. Detachably mounted on the rear portion of the main frame is a grooved track-way 3 which co-operates through anti-friction balls 4 with the slide bar 5 of a traveling platen carriage which further includes a pair of parallel arms 6 fixed to the bar 5 near its ends and extending upward and forward therefrom.

As more fully disclosed in my co-pending application Serial No. 137,014, filed December 14, 1916, the trackway 3 is provided with arms 3^a having hooked or slotted por-

tions 3^b that are adapted to detachably engage with pins 1^a projecting laterally outward from the sides of the frame 1. The construction enables the trackway 3 and the carriage which it supports to be readily removed and replaced, this being so whatever position in its travel along the trackway the carriage may have reached or may occupy.

Fixed to the arms 6 are supplementary arms or platen frame pieces 7 which provide bearings for the shaft 8 of the rotary platen 9. Co-operative with the front face of the platen are a series of ball bearing type bars 10 having a stationary fulcrum 11 and each connected through a link 12 with a lever 13 fulcrumed at 14 on a stationary support 15, the tail 13^a of each lever being connected to a restoring spring 16. A link 17 connects each lever 13 with one arm of a bell crank 18, the other arm whereof is connected to an upright key stem 19 provided with a key or button 20, said key stem bearing in a plate 21 fixed to the main frame. In addition to the printing keys 20 there is provided a space key or bar 22, from the middle portion whereof depends a stem or arm 23 which is controlled and guided by a spring pressed lever frame 24. Said stem is connected at its lower end to a crank arm 25 projecting laterally from a rock shaft 26 extending fore and aft of the machine and provided near its rear end with an oppositely projecting crank arm 27 overlying which is the forward or free end of a crank arm 28 fixed to a dog rocker shaft 29 (Figs. 90 1 and 5) which extends transversely of the machine and bears at its ends on pivot screws 30 secured in the end frames or plates 1. Connections are made between the dog rocker shaft and a curved universal bar 95 frame 31 which is vertically arranged in rear of the type bars and is operative by the tails 13^a of the levers 13. Said universal bar frame is supported and guided by crank arms 32 which rise from a rock shaft 33 near 100 the ends thereof, said rock shaft bearing in the sides of the base above the dog rocker shaft, the free ends of said crank arms 32 being pivotally connected to lugs or projections 34 fixed to the frame 31. The connections proper between the universal bar frame and the dog rocker shaft comprise a crank arm 35 fixed about centrally to the dog rocker shaft and projecting upward therefrom, a lateral pin 36 near the upper end 110

of said crank arm 35 engaging in a slotted lug or extension 37 fixed to the dog rocker frame and projecting rearward therefrom. The shafts 33 and 29 are caused to rock in 5 unison by connections comprising crank arms 38 and 39 fixed respectively to said shafts near their left-hand ends and connected by a vertical link 40. A restoring spring 41 is connected at one end to a crank arm 42 fixed 10 to the rock shaft 33 at its right-hand end, the other end of said spring being connected to a crank arm 43 fixed to the shaft 29 near its right-hand end. The construction is such that when one of the printing keys is operated 15 motion will be transmitted to the universal bar frame 31 through the tail 13^a and from said universal bar through the described connections to the dog rocker shaft 29. Also when the space key 22 is actuated 20 it will rock the shaft 26, causing the crank arm 27 to actuate the crank arm 28 and rock the shaft 29, to which said crank arm 28 is fixed. The printing instrumentalities, space bar and universal bar construction heretofore 25 described are like the corresponding parts found in the No. 10 Smith Premier machine and are not claimed specifically by me.

The leftward step-by-step movements of 30 the carriage to space between letters and words are caused and controlled by motor or spring drum and escapement mechanisms which are mounted on a detachable frame best shown in Fig. 4 where it is indicated as 35 a whole by the reference numeral 44. Said frame is composed preferably of a single plate or sheet of metal which is cut out as shown both for the sake of lightness and to accommodate various devices including 40 those which it supports. The frame or plate 44 is arranged at the rear and lower part of the machine behind the type bar system and inclines upward and forward, being secured at its ends by screws 45 to lugs 46 45 on the end plates 1. There are four of these screws 45 and by removing them the frame 44, together with the motor and escapement mechanisms, may be readily and expeditiously removed from the machine. Headed 50 screws 47 which pass freely through slots 48 in the plate 44 adjustably secure a U-shaped cross bar or bracket 49 to said plate at its left-hand end portion, said bar bridging an opening 44^a in said plate and providing 55 a support for a casing or stationary drum 50 which houses, as best shown in Fig. 2, a coiled spring 51, the outer end whereof is anchored to the casing 50. Fixed to and 60 and projecting rearward and upward from the central portion of the bracket 49 is a pin or stationary shaft 52 which provides a bearing for the hub 53^a of a gear wheel 53. As shown herein the gear wheel is made as 65 a separate piece from its hub to which it is secured by screw 54 that are threaded into a

flange formed integrally with said hub. The inner end of the spring 51 is secured to said hub and the tendency of said spring is to turn the gear wheel in the direction of the arrow in Fig. 4. Displacement of the gear 70 wheel from its bearing or shaft 52 is prevented by a headed screw 53^b which is threaded into the end of the shaft 52. Between the head of the screw and the outer face of the gear wheel are arranged certain 75 devices included in the back spacing mechanism which forms the subject-matter of my co-pending application, Serial No. 854,429, filed August 1, 1914 and need not be particularly described herein. The gear wheel 80 53 may be employed as a tension adjuster and by turning it in the opposite direction from the arrow the tension of the carriage spring 51 may be increased. This may only be done, however, when the platen carriage 85 is removed. Normally the teeth 54 of said gear wheel mesh with rack teeth 55 formed at the lower rear side of a rack bar 56 that is suitably secured to the lower end portion of the slide bar 5 (Fig. 1). Said rack bar 90 95 inclines downward and rearward and its forward side at right angles to the rack teeth 55 is formed with teeth 57 providing a rack for coöperation with the escapement devices as hereinafter described. When the 100 platen carriage is removed and the rack 55 is disconnected from the gear teeth or circular rack 54, the tendency of the main spring to run down is prevented by a detent or locking device in the form of a pawl 105 58 pivoted at 59 to the frame 44 and provided with an angular tail piece or extension 60 carrying an anti-friction roll 61 which is adapted to coöperate with the under part of the slide bar 5 when the carriage is 110 115 in place at which time the pawl tooth is maintained inoperative out of the path of the gear teeth 54. A spring 62 coiled around the pivot 59 tends constantly to press the pawl 58 into engagement with the teeth 54 120 125 so that when the track-way 3 and the platen carriage are detached, freeing the roll 61, said spring operates to throw the pawl into the gear wheel and automatically lock the carriage motor, preventing it from running down. From this construction it will be noted that the carriage may be removed at any point in its travel and that the locking pawl becomes instantly effective whenever the carriage is removed. On replacing the 130 carriage the under part of the slide bar 5 engaging the roll 61 will automatically force the pawl tooth out of the gear wheel, overcoming the spring 62.

The motor or spring 51 acting through the 125 gear and rack connection 54, 55 tends constantly to urge the carriage leftward but leftward movements are ordinarily controlled and regulated by escapement devices next to be described. Arranged in an open- 130

ing 44^b centrally of the plate 44 is a shaft 63 which at its upper end is reduced and bears in an opening in said frame, the lower end of said shaft being also reduced and bearing in an opening in a block 64 detachably secured by screws 64^a to said frame (Figs. 1 and 4), this construction enabling any looseness in the shaft due to end thrust to be taken up. Rotatably mounted on said shaft near its upper end is a pinion 65 provided with a hub portion 66 which abuts against a cross pin 67 extending through the shaft, said cross pin acting as a stop to limit upward movement of the pinion 65 lengthwise of the shaft. Downward movement of said pinion is prevented by a shoulder 63^a formed between the body of the shaft and the slightly reduced portion thereof on which said pinion bears. Said pinion meshes normally with the rack teeth 57 and is adapted to transmit movement to the shaft 63 by means of a clutch member 68 which is rotatably and slidably mounted on the shaft below the pinion 65 and is provided at its upper end with ratchet teeth 69 which mesh with corresponding ratchet teeth 70 formed in the under face of the pinion. Fingers 71 projecting downward from the clutch member at opposite sides of the shaft slidably engage with notches or slots 72 cut in a flange 73 on said shaft, the construction being such that the clutch member is forced to turn always with the shaft. Key controlled devices (not shown) engage in a circumferential groove 74 in the clutch member and are operative to move said clutch member downward on the shaft to disengage the ratchet teeth 69 from the ratchet teeth 70 so as to permit the pinion 65 to turn freely on the shaft, thus releasing the carriage and permitting it to run freely leftward under the pull of its motor. The downward or releasing movement of the clutch member is limited by the flange 73 which acts as a stop. Such downward movement is in opposition to a spring 75 which is coiled around the shaft 63 and co-operates with the lower ends of the fingers 71, said spring operating to maintain the clutch member normally engaged with the pinion 65 and also to restore said clutch member to engagement after the releasing operation. The lower end of said spring abuts against a hub-member 76 secured by set screws 77 in fixed relationship with said shaft 63. Said hub member is provided with a flange 78 to which is secured as by riveting an escapement wheel 79 provided with a series of long, radial teeth 80. To the lower ends of said hub member is fixed by screws 81 a ratchet wheel 82 with which co-operates a gravity pawl 83 pivoted at 84 to a bracket 85 adjustably secured by a screw 86 to the plate 44. The pawl and ratchet 83 and 82 co-operate to prevent backward turning of the escapement wheel.

Cooperative with the teeth 80 of the escapement wheel are escapement dogs which are mounted on the shaft 29 (Figs. 1 and 5-11). There are two of these dogs, numbered respectively 87 and 88 mounted side by side with their working faces transverse of the plane of the escapement wheel, said dogs being arranged or housed in a depression or slot 89 in a dog rocker 90 and pivoted co-axially on a pivot pin 91 bridging said depression near the bottom thereof as best appears from Fig. 10 which is an end view taken from the left-hand side, Fig. 9 being the corresponding view from the right. The dog rocker is inclined rearward and upward from the rock shaft 29 at an angle parallel with the plane of the escapement wheel. Said dog rocker is in the form of a block which is detachably secured by set screws 92 to the rock shaft 29. Coiled springs 93 housed in depressions 94 in the dog rocker co-operate one with each dog and tend constantly to press their respective dogs normally outward or toward the left. Outward movement of said dogs is limited by a T-shaped stop 95 fixed to said dog rocker, the stem thereof passing inward between the dogs and the head comprising oppositely projecting stop portions proper. The escapement is a "convertible" one, and may be made "ordinary" or reverse at will by alternately making each dog either a fixed dog or a stepping dog. This result is accomplished in the present instance by hand controlled devices mounted on the rock shaft 29 and comprising a rod or shaft 96 bearing near its outer end in an arm 97 fixed by a screw 98 to the crank arm 39 and consequently rigid with said rock shaft. Said shaft 96 extends outward through a slot 1^a in the adjacent end plate 1 and is provided with a finger button or key 99 by which it may be turned back and forth. The inner end portion of said rod or shaft passes between the two dogs 87 and 88 and bears in a hole in the dog rocker, the end of said shaft projecting through said dog rocker and supporting a coiled spring 100 which is confined between the dog rocker and a cross pin 101 fixed to said shaft near its end. This spring constantly tends to draw the shaft 96 rightward. A stop lug 102 projects from a collar 103 suitably fixed to the rod or shaft 96 to the left of the dogs. By turning the shaft said stop 102 may be caused to co-operate either with one dog or the other so as to fix its relationship with respect to the dog rocker. Shoulders 87^a and 88^a formed in the working faces of the dogs limit turning movements of the stop lug or fin 102 and the spring 100 maintains said stop lug frictionally engaged with either dog after it has been turned to properly engage therewith by manipulation of the finger button 99.

BEST AVAILABLE COP

4

1,237,437

Under all conditions the rear dog 87 is normally engaged with the escapement wheel. When the adjustable stop 102 is turned forward so that it co-operates with the dog 88 as in Fig. 6 the spring 93 of said dog is overcome and the dog is held rigidly on the dog rocker during escapement operations and acts as a fixed dog. At this time the dog 87 is free to be moved outward or away from the rocker by its spring 93 when released from the escapement wheel until arrested by the rear portion of the T-stop 95 as shown in Fig. 6 from which the escapement wheel is omitted. This figure, it will be understood shows in top plan the positions of the dogs when a key is depressed at which time the dog 88 will be engaged with the escapement wheel. Upon the release of the depressed key the dog rocker will swing back to normal position, the dog 87 passing behind the engaged or active tooth of the escapement wheel, and when the rigid dog 88 has moved far enough forward to release the engaged tooth the escapement wheel will begin to turn and the oncoming tooth thereof will engage with the dog 87, overcoming its spring 93 and moving said dog back until it is arrested by engaging with the bottom of the depression 89, thus permitting the escapement wheel to turn a distance corresponding to the distance between two of its teeth and effecting a letter space movement of the carriage toward the left.

When it is desired to reverse the feed so as to cause the escapement movement to take place during the depression of the printing keys, the finger button 99 is turned to effect a half revolution of the stop lug 102 from the Fig. 6 position to the position shown in Figs. 5, 7 and 8. During this turning movement the stop will swing downward and rearward, releasing the dog 88 so that it will be under control of its spring 93. After releasing said dog the inner end of the stop 102 will engage with a beveled or inclined portion 87^b of the outer face of the dog 87 and will cam said dog inward, overcoming its spring 93 so that it will become the fixed dog and will be maintained in rigid relationship with the dog rocker during escapement operations. When such operations take place the rigid dog 87 will swing rearward out of engagement with the escapement wheel and the stepping dog 88 will swing into the plane of said escapement wheel so that toward the end of the key depression the escapement wheel will turn to overcome the individual spring of said dog 88 and cause a letter space advance movement of the carriage. During return movement of the dog rocker to normal position the loose or stepping dog 88 will be freed so that it will be again moved outward by its spring until arrested by the forward portion of the T-stop 95, and when the rear dog 87 reengages with the escapement wheel the parts will be in position ready for beginning the next letter space movement. When it is desired again to convert the escapement the stop 102 is turned back to the Fig. 6 position, during which movement it will act against an inclined edge 88^b of the dog 88 to cam said dog back or inward.

The bevels 87^b and 88^b are oppositely inclined and provide a sort of pocket in which the stop 102 may be seated as shown in Fig. 11. The ends of the stop are preferably beveled to facilitate camming operations on the dogs and the beveled or pointed end fits loosely in the pocket, this construction serving both to center the stop and to permit outward pivotal movement of both dogs until arrested by the stop 95 as shown in said Fig. 11. With the parts in this relationship both dogs are loose and the escapement is set to permit a letter space movement on the down stroke as well as one on the up stroke of the key, thus providing for a double space at each key stroke. This spaces the letters twice as far apart as usual, a style of printing which is sometimes favored for headings, or to emphasize words or statements.

Various changes may be made without departing from my invention.

What I claim as new and desire to secure by Letters Patent, is:—

1. In a typewriting machine, the combination of a removable traveling carriage, a rack connected therewith, a motor, a gear wheel connected with said motor and meshing with said rack, a pawl, means constantly tending to press said pawl into engagement with said gear wheel, said means being normally maintained ineffective by said carriage but the removal of the carriage at any point in its travel rendering said means effective, the mere replacement of the carriage automatically rendering said means ineffective again.
2. In a typewriting machine, the combination of a removable traveling carriage, a rack connected therewith, a carriage motor, a gear wheel connected with said motor and meshing with said rack, a pawl provided with a tooth adapted to engage said gear wheel and having a portion constantly engaged by said carriage thereby normally holding said tooth out of engagement, and a spring constantly tending to press said tooth into engagement with said gear wheel, the removal of the carriage at any point in its travel instantly rendering said spring effective, the mere replacement of said carriage automatically rendering said pawl ineffective again.
3. In a typewriting machine, the combi-

nation of a traveling carriage, a carriage motor, separable rack and gear connections between said carriage and said motor, and means for automatically preventing said motor from running down when said rack and gear connections are separated, said means comprising a normally inoperative pawl provided with a spring which tends constantly to force said pawl into engagement with 10 said gear connection but which is normally rendered ineffective by said carriage; said rack and gear connections being separable at any point in the carriage travel and said spring becoming effective the instant said separation takes place, the mere replacement of said carriage automatically rendering said pawl ineffective again.

4. In a typewriting machine, the combination of a carriage, a rack member provided with two sets of teeth, said teeth being disposed at angles to each other, carriage motor devices comprising a gear wheel meshing with one of said sets of teeth, and escapement devices comprising an escapement wheel and a feed pinion, said feed pinion meshing with the other of said sets of teeth.

5. In a typewriting machine, the combination of a carriage, a rack connected therewith, a carriage motor, a gear wheel connected with said motor and meshing with said rack, and a spring pressed pawl normally maintained inoperative by said carriage but adapted to engage with said gear wheel to prevent the same from turning in one direction and the motor from running down, said pawl however permitting the gear wheel to be turned in the opposite direction to increase the motor tension.

6. In a typewriting machine, the combination of a carriage, an escapement wheel connected therewith, a pair of coöperative dogs, a dog rocker, a dog rocker shaft, and means supported partly on said dog rocker 45 and partly on said shaft and operative on said dogs to convert the escapement.

7. In a typewriting machine, the combination of a carriage, an escapement wheel connected therewith, a pair of coöperative dogs, a dog rocker, a dog rocker shaft, and dog converting means comprising a rod provided with a finger piece outside of the machine and having a bearing fixed to said shaft and a stop operative by said rod and coöperative at will with either of said dogs.

8. In a typewriting machine, the combination of a carriage, an escapement wheel connected therewith, a pair of coöperative dogs, a dog rocker, a dog rocker shaft, and dog converting means comprising a rod provided with a finger piece outside of the machine and having a bearing fixed to said shaft and a stop operative by said rod and coöperative at will with either of said dogs,

said stop being also settable to free both 65 dogs at the same time.

9. In a typewriting machine, the combination of a carriage, an escapement wheel connected therewith, a pair of coöperative spring pressed dogs, a dog rocker, a dog rocker shaft, and a rotary stop for locking either of said dogs against movement relative to said dog rocker, and a spring coöperative with said stop for overcoming the 75 dog springs.

10. In a typewriting machine, the combination of a carriage, an escapement wheel, a pair of coöperative dogs, individual springs therefor, a dog rocker supporting said dogs, a rotary hand controlled stop, and a spring coöperative with said stop and stronger than said dog springs, said stop being settable to lock either of said dogs in fixed position on said dog rocker.

11. In a typewriting machine, the combination of a carriage, an escapement wheel, a pair of coöperative dogs provided with oppositely beveled side edges, individual springs therefor, a dog rocker supporting 90 said dogs, a rotary hand controlled stop provided with beveled edges coöperative with the beveled edges of the dogs to cam said dogs against their springs, and a spring coöperative with said stop and stronger than 95 said dog springs, said stop being settable to lock either of said dogs in fixed position on said dog rocker.

12. In a typewriting machine, the combination of a carriage, an escapement wheel, a pair of coöperative dogs provided with oppositely beveled side edges, individual springs therefor, a dog rocker supporting said dogs, a rotary hand controlled stop provided with beveled edges coöperative 100 with the beveled edges of the dogs to cam said dogs against their springs, and a spring coöperative with said stop and stronger than said dog springs, said stop being settable to lock either of said dogs in fixed position on 105 said dog rocker and also being settable to inoperative position in the pocket formed by said beveled side edges.

13. In a typewriting machine, the combination of a carriage, an escapement wheel connected therewith, a pair of coöperative dogs, individual dog springs, a dog rocker, a dog rocker shaft, a rod provided with a finger piece outside of the machine and having a bearing fixed to said shaft, said rod 115 also bearing in said dog rocker, a stop operative by said rod and coöperative at will with either of said dogs, and a spring surrounding said rod and tending constantly to move it longitudinally in one direction, 120 said spring acting in opposition to the individual dog springs.

14. In a typewriting machine, the combination of a carriage, an escapement wheel

connected therewith, a pair of coöperating dogs, individual springs for said dogs, a movable dog supporting frame, a rod provided with a finger piece and mounted on 5 said frame, a stop on said rod coöperative at will with either of said dogs, and a spring for pressing said rod in opposition to said dog springs.

Signed at the borough of Manhattan, city of New York, in the county of New York, 19 and State of New York, this 6th day of August, A. D. 1914.

CLIO B. YAW.
